UNITED STATES PATENT OFFICE

2,524,058

ELECTROMECHANICAL HAIR CURLER

Sori Bokri Kamara, Chicago, Ill.

Application July 18, 1947, Serial No. 761,807

5 Claims. (Cl. 132—34)

1

The present invention relates to hair curlers for use in hairdressing establishments, in the home and elsewhere for hair waving and conditioning purposes and has more particular reference to an electro-mechanical-type characterized by a motor driven curling mandrel.

Needless to say, powered revoluble winding and curling mandrels in hair curler constructions are not new. As a matter of fact, many and varied efforts and attempts have been made by others in this line of endeavor to properly devise an unqualifiedly acceptable electro-mechanical curler of the rotatable-type. Then too, and in addition, it is not novel to utilize, in these types of curlers, heating cores and elements. It follows, that since the broad and fundamental aspects are old, factors of relative novelty pertain, primarily noticed, to a choice and selection of novel elements, their coordination and attending results. It follows that it is the purpose of the instant invention to structurally, functionally and otherwise improve upon known types of powered hair curlers, this through the instrumentality of what is believed to be a more adequate and satisfactory structural organization, a particular adaptation thereof which is possessed of refinements and other accomplishments needed in the trade.

Other objects and advantages will become more readily apparent from the following description and the accompanying illustrative drawings.

In the drawings, wherein like numerals are employed to designate like parts throughout the views:

Figure 1 is a view in section and elevation showing a complete hair curler of the motor operated type constructed in accordance with the principles of the present invention;

Figure 2 is an enlarged cross section on the line 2—2 of Figure 1, looking in the direction of the arrows;

Figures 3, 4 and 5 respectively, are enlarged cross sectional views on the planes of the lines 3—3, 4—4, and 5—5 of Figure 1, all looking in the direction of the indicating arrows.

Briefly and broadly, the structure, in unitary or overall appearance, is of the so-called pistol-grip type and, in practice, includes an angular grip and trigger-like part forming the conveniently accessible start-stop device.

The main body or casting, as a unit, is denoted by the numeral 6 and includes an open bottom cylinder 7 constituting a hand-grip as well as a holder for an appropriate electric motor 8. The current supply cord 9, leading to the motor is

2

provided with a suitable switch 10 and floor plug, or the like (not shown) to supply the motor with current. The arbor or shaft 11 has a conical driving terminal 12 in constant friction driving contact with a propelling disk 13. The disk has a marginal brake flange 14 to accommodate a lateral brake shoe 15 formed on one end of a substantially L-shaped trip-lever 16. The trip-lever is provided with a return and retaining spring 17 of an appropriate type and the portion 18 of the trip lever is pivotally mounted between lugs or ears 19, as shown at 20 (see Fig. 5 in particular). The lateral left-hand end portion of the body is fashioned into a reduced cylindrical bearing 21 having a collar-like bushing 22 receiving and supporting a rotatable hollow curling mandrel 23. This mandrel is closed at its outer end and serves to house an appropriate electrical core or heating element 24, the same supported at one end as at 25. The opposite end of the core projects through and beyond the mandrel and into an insulator sleeve 26 where it receives current from a suitable connector 27 connected with the motor. The aforementioned friction disk is provided with 28 a hub 28 fastened as at 29 on the mandrel. It will be noted in the upper right in Figure 1 that the intermediate or junctional portion between the hand-grip 7 and bearing 21 is provided with an accommodation slot permitting protrusion and proper mounting of the brake flange and friction disk. This arrangement also provides an ideal arrangement to support the trigger 16 and to position the brake finger 15 in proper relation to the brake flange. What is more, at this point and interiorly the body is fashioned with an appropriate enlargement 30 which is socketed for anchorage of one end of the mandrel 23 and which accommodates the insulator 26 which, in turn, provides for convenient assembling and anchorage of the heating element.

The sheath-like hair clamping blade 31 includes a channel portion 32 which conforms to the mandrel. It also includes usual attaching ears 33 which are pivotally mounted at 34 on diametrically opposite sides of the mandrel. The lateral operating end portion terminates in a hook 35 which is connected with an operating ring 36 surrounding the bearing. A suitable spring 37 is employed and is interposed between the member 31 and the mandrel to normally close said member for hair clamping and curling accomplishments.

In operation, the electric motor provides the source of energy and, through the medium of the drive shaft imparts rotary motion to the friction

energy transmission disk 13 with the consequence that the mandrel is rotated for winding and curling purposes. So long as the brake shoe or finger 15 is applied to the brake flange, the mandrel stands still. The speed and degree of rotation is therefore determined by proper, as well as carefully regulated manipulation of the brake shoe, this by way of the trigger 16. Thus, we have on the hand-grip conveniently actuatable "stop-go" means for the revoluble mandrel. Since the hair is wound on the mandrel and the mandrel turns as the hair is turned by way of the blade 31, it is desirable that the ratio of speed between the motor driven arbor and mandrel be relatively slow in order to avoid over-winding, or winding in a manner which is too rapid for safety.

As previously stated, motor operated mandrels and hair curlers are old and the method and use of same is well known to hairdressers in beauty parlors and the like. In the circumstances, it seems not necessary to dwell upon features, advantages, construction and mode of operation.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

I claim:

1. A motorized rotary hair curler of the class described comprising a body including a bearing, a mandrel mounted for rotation in said bearing, said mandrel being provided with a friction driving disk, an obliquely disposed motor in said body including a drive shaft in frictional driving contact with said disk, the end of the shaft contacting the disk being of conical form, said friction disk being provided with a marginal brake flange, and a hand-controlled brake member on said body cooperable with said flange.

2. A motorized rotary hair curler of the class described comprising a body including a bearing, a mandrel mounted for rotation in said bearing, said mandrel being provided with a friction driving disk, an obliquely disposed motor in said body including a drive shaft in frictional driving contact with said disk, the end of the shaft contacting the disk being of conical form, said friction disk being provided with a marginal brake flange, and a hand-controlled brake member on said body cooperable with said flange, said brake member being of general L-shaped form and the free end thereof constituting a brake shoe and being pressed by spring means into friction-retaining contact with said flange.

3. A hair curler of the class described comprising a body including a cylindrical portion constituting a hollow hand-grip, said body also includ-

ing a lateral bearing, a mandrel mounted for rotation in said bearing and having a friction disk extending into said body and provided with a marginal brake flange, a motor in said cylindrical portion, said motor having a conical-tipped shaft to contact the said disk, said body having a slot and the brake flange on said disk being exposed to the exterior by way of said slot, an L-shaped trip pivotally mounted on said body having a finger-piece and a part constituting the brake shoe, said brake shoe resting in normal retaining contact with said brake flange.

4. A hair curler of the class described comprising a body including a cylindrical portion constituting a hollow hand-grip, said body also including a lateral bearing, a mandrel mounted for rotation in said bearing and having a frictional disk extending into said body and provided with a marginal brake flange, a motor in said cylindrical portion, said motor having a concially-tipped shaft to contact the said disk, said body having a slot and the brake flange on said disk being exposed to the exterior by way of said slot, an L-shaped trip pivotally mounted on said body having a finger-piece and a part constituting a brake shoe, said brake shoe resting in normal frictional contact with said brake flange, and a sheath-like blade pivoted on said mandrel provided with a ring in one end surrounding said bearing.

5. An electro-mechanical hair curler of the class shown and described comprising a body embodying a hollow hand-grip, said hand-grip being open at one end and provided at its opposite end with a bearing, a hollow mandrel mounted for rotation in said bearing and having a friction type motion transmitting disk, said disk being mounted in said body, said body having a slotted portion and the peripheral portion of said disk projecting to the exterior of the body through said slotted portion, the peripheral portion of said disk having a marginal flange, a lever exteriorly pivoted on said hollow handle and including a spring urged handle portion and a brake shoe, said brake shoe being in normal spring pressed contact with said flange, and a motor fitted into said handle by way of the open end of the handle and including a shaft in friction driving contact with said disk.
